BOILER

August B. Blome, Mount Vernon, N. Y., assignor
to The Superheater Company, New York, N. Y.

Application November 14, 1935, Serial No. 49,706

5 Claims. (Cl. 122—460)

The present invention relates to boilers of the locomotive type and has for its general purpose the improvement of such boilers. The more specific form of such boilers with which the invention is concerned is one in which there is a water-tube fire-box followed by a fire-tube section located forward of it. The detailed points of improvement will become clear from a reading of the following specification.

10 The invention will be described with reference to the accompanying drawings. In these, Fig. 1 is a lateral elevation of a locomotive with a boiler in accordance with my invention showing the general disposition of the various parts. Fig. 2 is an enlarged view, partly in lateral elevation and partly in central longitudinal section of the rear portion of the locomotive. Fig. 3 is a section on line 3—3 of Fig. 2 looking in the direction indicated by the arrows; Fig. 4 is 15 a section on line 4—4 of Fig. 2 looking in the direction indicated by the arrows; and Fig. 5 is 20 a section of a valve used in the arrangement.

Referring first to the general arrangement as indicated in Fig. 1, the fire-box section is designated by the reference character A and the fire-tube section by the reference character B. Above them and extending from the rear end of the fire-box to the forward end of the fire-tube section is a drum C. Between the fire-box section A and the fire-tube section B is located the superheater D. In the particular form shown, an air preheater is located at E forward of the fire-tube section, the air preheated in it being 30 conducted to the fire-box by means of the duct F.

It is necessary in modern locomotives to provide ample combustion space in the furnace. The lateral limitations imposed by the track 40 clearances are very severe and volume can be added only by extending the fire-box and combustion space longitudinally. With the modern tendency to higher pressures, the old stayed flat-sheet fire-boxes are out of the question and 45 designers have therefore resorted to making up the walls of the fire-box and combustion chamber of water tubes. This is sound engineering and is followed in my design. However, when these water tubes are placed vertically as they 50 have been generally in the past for insuring rapid circulation through them, a great number of joints has resulted to connect the numerous tubes to the upper and lower manifolds or headers. This number has been cut down at times by 55 bifurcating the tubes making up the water wall

and placing the two pipes constituting each unit in a plane parallel to the axis of the locomotive. But even with this expedient the number of joints is very large and in addition, the resulting structure is extremely rigid and the problem of leaks at the joints from unequal expansion is serious.

I am aware that attempts have been made in the past to place the tubes constituting the wall and roof of the combustion chamber horizontally or approximately so. In one case in particular this has been done, the tubes sloping upward in a forward direction to ensure circulation. The length of tubes which can be used in this construction is evidently strictly limited. The circulation must be very lively to protect the tubes sufficiently and if the tubes are made beyond a certain length, the inclination cannot be sufficient to insure such circulation.

In the arrangement according to my invention the tubes constituting the side walls and roof of the fire-box are placed horizontally and are preferably bifurcated. Their ends are expanded into the rear header 1 and front header 3 (see Fig. 2). At the points where they are expanded into these headers, these tubes are single as indicated at 5 and 7. Throughout the greater part of their length, however, they are bifurcated as at 9. They are arranged to enclose a space which in transverse section has the form of an inverted U, the two legs of which constitute the side walls and the top of which constitutes the roof of the fire-box. By bifurcating them as described and placing the two tubes constituting the several units into the upright and horizontal planes, these tubes can be grouped closely enough to constitute a substantially continuous wall and roof. There will of course outside of them be a further closure as indicated at 11 and 13.

The rear end is closed by a refractory wall 15 with a suitable opening 17 for firing.

The grate is located at 19.

At the forward end the single tube portions of the elements in the two walls are preferably made of considerable length as shown at 7a. As a result, these tubes in this forward portion will be spaced apart. This is done to provide means for installing and supporting the superheater elements which are made of special design for this purpose. These superheater elements are secured at their inlet ends to a header 21 and loop through between adjacent tubes 7a across the combustion chamber. The left hand end (as viewed in Fig. 4) of these loops rests on the tubes

1a on the left hand side. Each superheater element therefore comprises a plurality of horizontal loops arranged in a vertical row. The lower ends of the elements are bent toward and 5 are secured to the lower header 23. From this header the steam is conducted through the throttle 25 to the steam pipe 27 which carries it to the two steam chests.

Forward of this water tube section just described, there lies the fire-tube section B. This is made up of a cylindrical sheet 29 and two tube sheets, the rear of which shows at 31. Extending between these two tube sheets are the fire tubes 33 which conduct the hot gases forward 10 through this fire-tube section into the smokebox, through which they pass in any preferred manner to the stack 35.

The drum C extends as stated above over both the water-tube section and the fire-tube section. 20 In the particular form shown, there is only one drum, centrally located, but this can obviously be varied by having two drums, one on each side. The forward portion of the drum C is preferably flattened as at 37 to be secured to a correspondingly flattened spot on the fire tube section. The drum C communicates with the fire tube section through openings 39. 42 indicates the normal water level in the drum. Extending from a point above this water level downward through the 25 drum wall and the wall of the fire-tube section and terminating inside of the fire-tube section but adjacent to its highest point, are tubes 41. Any desired number of these can be provided. Their function is to conduct steam which forms 30 in the fire-tube section into the steam space of the drum C. The object of the openings 39 on the other hand, is to permit downward flow of water from the drum C to the fire-tube section B.

At their rear end communication between the 40 water tube section and the drum is established by means of a series of tubes 43 arranged in any preferred manner, but so that ample area is provided for the flow of the mixture of steam and water from the water-tube section to the drum.

45 From fire-tube section B to water-tube section A there is provided a connection 45. In this connection there is a steam-driven pump 47. This pump forces water out of the fire-tube section into the forward end of the water-tube section and its capacity and normal rate of operation are such that preferably 5 to 7 times as much water is circulated through the water-tube section as is evaporated in it. This results in a rapid 50 protective circulation through the water tubes of the fire-box section and in a good distribution of water among them. The water, together with the steam generated in the water tubes, is delivered into the drum C through the connections 43 and in the drum the steam separates out and 55 the excess water returns through openings 39 to the fire-box section. The steam is taken by means of the connecting tubes 49 to the superheater header 21.

Feed water is forced into the boiler by pump 60 51. It reaches this pump from the tender through pipe 53 and is delivered to the feed water heater 55 by means of a connecting pipe 57. From this feed water heater it is conducted to the boiler by means of pipes 57, three-way 65 valve 61 and pipe 58.

It is essential that the water tubes in the water-tube fire-box be protected by positively circulating water through them. Should the pump 47 fail, this circulation would cease and a 70 dangerous situation would at once arise. To take

care of such a situation, I make the following provision. I connect the pipe 45 to the three-way valve 61 by means of the connecting pipe 59. This three-way valve 61 is normally set as indicated in Fig. 5. Communication is thereby established through the pipes 57 and 58 and communication from 57 to 59 is interrupted. Should the pump 47 break down, the three-way valve is set so that communication is established between 57 and 59, and pipe 58 is closed off. With 10 such a setting of the valve, the feed water is delivered directly into the water-tube section, circulates through it and is delivered into drum C and thence to the fire-tube section. To prevent the water under these conditions from flowing 15 back through pump 47 into the fire-tube section B, a check-valve 40 is provided.

The circulation through the water tubes is of course very much slower under these conditions and the whole situation is one of emergency—the 20 locomotive can be operated, but only at very reduced rating. This will, however, enable the engineer to move his train to the nearest point where repairs can be made.

The essential features as will be gathered from 25 the above are that by my arrangement horizontal water tubes of any desired length can be utilized for constructing the side and top walls of the fire-box. A positive and enhanced circulation through these water tubes is provided and 30 in case of failure of this rapid circulation, a slow but nevertheless positive circulation for the emergency is provided.

Obviously, in practicing my invention some 35 variations from the form described above in detail will occur without any real departure from the spirit of the invention.

What I claim is:

1. In a locomotive, a fire-box section comprising front and rear headers and horizontal water 40 tubes connecting them and forming the side and top walls of the fire-box, the tubes of the side walls being bifurcated for the major part of their length from the rear header forward but single for a distance adjacent to the front header, and 45 a tubular superheater comprising tubes extending across the forward portion of the fire-box and resting on said single tube portions.

2. Apparatus according to claim 1, the superheater comprising a plurality of elements each 50 made up of loops connected by return bends extending around the outer side of the single tube portions on one side of the fire-box, whereby the elements can be inserted and withdrawn without disturbing the water tubes. 55

3. In a boiler, a first steam generating section, a second steam generating section, a steam-and-water drum located higher than both of said sections, means including a pump for creating a positive circulation from the first boiler section 60 through the second boiler section to the drum and back to the first section, means to conduct steam directly from the first section to the drum, means to deliver feed water to the first section, means to take steam off the drum, and means 65 to bypass the feed water around the first section directly to the second section.

4. A boiler in accordance with claim 3, the first steam generating section being a fire tube section, and the second steam generating section 70 being a water tube section with horizontal water tubes surrounding the fire box on its two sides and top.

5. In a locomotive boiler, a fire-box section comprising front and rear headers and horizon- 75

tal water tubes connecting them and forming the side and top walls of the fire-box, said water tubes being of a length no less than fifty per cent of the total boiler length, a fire-tube boiler section forward of the fire-box section, means to deliver feed water to the fire-tube section, and means to circulate water from the fire-tube sec- 5

tion through the fire-box section in a direction counter to the flow of the heating gases comprising a connection from the fire-tube section to the front header, a connection from the rear header to the fire-tube section, and a pump in one of said connections. 5

AUGUST B. BLOME.
